CURRENT RESPONSIVE INSTRUMENT

Ralph M. Rowell, Lynn, Mass., assignor to General Electric Company, a corporation of New York

Application April 28, 1939, Serial No. 270,579

3 Claims. (Cl. 171—95)

My invention relates to current responsive instruments and concerns particularly instruments and current responsive devices of the dynamometer type.

5 It is an object of my invention to provide an improved iron core type of dynamometer instrument having a high current range and substantial freedom from voltage and current errors and in which the movable coil remains at a zero position and does not produce any torque when no current is flowing in the field coil, thus obviating the necessity for auxiliary or torque compensating coils.

Other and further objects and advantages will 15 become apparent as the description proceeds.

In carrying out my invention in its preferred form I provide a field structure having an outer pole piece and an inner pole piece, which is very nearly surrounded by the outer pole piece and 20 spaced to form an annular air gap 250° in length through which an eccentrically mounted coil may rotate. The inner piece has an opening through the center, through which pass one side of the coil and the shaft supporting the coil. The core 25 member including the inner pole piece is divided so as to have the general form of a U. There are arms or branches, which extend from the outer pole piece to the ends of the U to complete the magnetic circuit of the field. However, air gaps 30 are interposed between the inner pole piece and the arms leading from the outer pole piece in order to increase the reluctance in the path of magnetic flux which tends to be produced by the movable coil. A stationary or field coil is wound 35 around the neck or base portion of the outer pole piece. In the case of a wattmeter, for example, the field coil may be formed as a current coil and the movable coil as a potential coil of the instrument.

40 The invention may be understood more readily from the following detailed description when considered in connection with the accompanying drawing and those features of the invention which are believed to be novel and patentable will 45 be pointed out in the claims appended hereto. In the drawing, Fig. 1 is a front elevation, partially in section, with certain portions of the apparatus broken away for the sake of clarity, showing the laminated-core torque-producing unit of a dynamometer type instrument constructed in accordance with my invention. Fig. 2 is a side elevation of the arrangement of Fig. 1, also shown partially in section, with a portion of the apparatus broken away. Figs. 3 and 4 are fragmentary detail views 50 of two different shapes of laminations used in

the arrangement of Figs. 1 and 2; and Fig. 5 is a graph explaining the principle of operation of my apparatus. Like reference characters are utilized through the drawing to designate like parts.

5 Referring more in detail to Figs. 1 and 2, in the arrangement described, there is a movable coil 11 arranged to travel in an annular gap 12 which is of considerable length constituting the greater part of the periphery of a circle, for example, 270° or at least 250°, and there is a field coil 13 for producing magnetic flux across the gap 12 within which the coil 11 is arranged to travel. Although this arrangement of coils may be used for various types of dynamometer instruments such as alternating and direct current voltmeters and ammeters, for example, it is particularly useful with wattmeters and I shall describe the arrangement with particular reference to its use as a wattmeter. For this purpose it is usually most convenient to wind the movable coil 11 with relatively fine wire connected in series with a suitable multiplier or resistance coil to serve as the potential coil of the wattmeter and to wind the field coil 13 with a suitable number of turns of heavy wire to 20 serve as the current coil of the wattmeter. 25

In order to obtain a wide angle of movement of the rotatable current conducting coil 11, the field iron of the instrument is arranged with an inner annular pole piece 14 which is very nearly surrounded by an outer pole piece 15. One side of the coil 11 and the shaft 16 to which the said side of the coil 11 is secured pass through the center of the annular pole piece 14. The outer pole piece 15 is integral with a field member 17 which, in the arrangement shown, may be generally in the shape of a C with the pole piece 15 constituting a projection extending inwardly from the mid portion of the C, the projection or pole piece 15 having a circular notch therein for the inner pole piece 14. The field iron is completed by the core 18 which is generally in the shape of a U with the yoke portion forming the annular inner pole piece 14 and with leg portions 19 and 20 spaced to leave an air gap between them. 30 35 40

The end portions 21 and 22 of the C-shaped field 17 approach very closely to the sides of the ends 19 and 20 of the U-shaped core 18. Preferably the end portions of the field 17 and the core 18 do not come into immediate contact but leave 50 perceptible air gaps 23 and 24 for the purpose of reducing field saturation and overcoming wave form errors of the instrument. In the preferred arrangement which I have illustrated, although the air gaps 23 and 24 are relatively small and 55

less than the air gap 12 within which the outer side of the movable coil 11 travels, the air gap 12 in turn is less in length than the air gap 25 between the leg portions 19 and 20 of the U-shaped core 18.

It will be understood, of course, that the precise shapes of the field and core members are immaterial and that any shape may be employed which would provide a flux conducting path from the outer pole piece 15 to the inner pole piece 14. However, in order to avoid having the rotatable coil 11 subject to having force applied to it solely due to the action of current flowing through it, I prefer to have the core 18 constructed in some form of the nature of that shown where the portion of the material connected to the pole piece 14 is divided so as to have the air gap 25 between said divided portions, and preferably the core 18 has a relatively symmetrical configuration at least in the portion thereof close to the inner annular pole piece 14. It will be seen that in the arrangement illustrated the entire field structure is relatively symmetrical, so that flux produced by the field coil 13 mounted on the neck 26 of the pole piece 15 divides substantially equally between the branches 27 and 28 and between the leg portions 19 and 20 to the inner annular pole piece 14, where the two flux paths join, and the flux passes across the gap 12, back to the outer pole piece 15. The annular pole piece 14 may be regarded as having a gap 25 in the annulus with the core portions 19 and 20 extending from either side of said gap 25. My invention, however, is not limited to this precise arrangement since the air gap 12 is relatively uniform and causes the flux to distribute itself substantially evenly across the length of the air gap 12.

Although I have referred to the field members as field irons, it will be understood of course that my invention is not limited to the use of iron for the flux conducting portion of the apparatus but that any suitable material having relatively high permeability of the order of that of soft iron may be employed. I have found, for example, that an alloy of about 47% nickel and the balance iron is satisfactory. In connection with alternating current instruments, it will be understood of course that it is advantageous to have the field 17 and the core 18 constructed in the form of stacked laminations. By making the annular length of the circular opening or notch 12 in the pole piece 15 approximately 270° as shown, it will be seen that even with the coil 11 of finite width, a movement of the element exceeding 250° may be obtained.

For the purpose of extending the current range and also further decreasing the tendency of the potential coil 11 to deflect when there is no current in the current coil 13, I preferably modify the shape of some of the core laminations as illustrated in Fig. 4, and round off decidedly the corners 15' of the field pole piece 15. In an arrangement which I have found to operate successfully, every third lamination of the core 18 has the shape shown by the outline A (Fig. 4), with the shelf portion B, instead of having the shape shown by the outline C (Fig. 3). The portions B of the laminations of the shape A come substantially in contact with the tips D of the field pole piece 15.

When using only cores of the shape C, distinctly separated from the field pole piece 15, some difficulty has been experienced from saturation at high current, which may occur with low line voltage or low power factor at the rated

power of a wattmeter. It is important that a wattmeter having a five-ampere current coil, for example, should be able to measure full scale watts at ten amperes, for example, without an appreciable error in indication.

With the particular design illustrated in the drawing using only core laminations of the shape C, an error of approximately 1.5% may be encountered at ten amperes in the case of an instrument having a five-ampere current coil. It is not feasible to attempt to decrease the error by decreasing the current flux and increasing the potential flux because this would result in tending to increase the voltage errors. Even with the voltage errors made relatively small by the symmetrical design illustrated, there is still a slight tendency for the movable coil 11 to swing toward the center of the scale so that the reluctances of the portions of the air gap on either side of the coil will be balanced. Obviously this effect would be increased by modifying the design to make the potential flux relatively excessive.

By the use of the shelf portions or projections B in the laminations A, current errors are reduced in the following manner. The projections B, by forming a magnetic shunt across the air gap, reduce the flux in the gap. However, when the current is increased to a value approaching ten amperes (assuming a five-ampere coil) the flux density becomes so great that the projections become saturated and shunt less flux across the gap. This compensates for current errors which would otherwise occur due to increasing saturation of the magnetic circuit as a whole and the decreasing ratio of magnetic flux to current for the higher values of current. The use of laminations shaped substantially as at A is found to produce flat compensation at ten amperes and a reduction of the current error to less than one per cent up to twelve amperes, in the case of an instrument having a five-ampere coil. The reduction of the reluctance of the air gap at the ends of the scale also decreases the tendency of the coil 11 to swing to its center scale position. In this manner both the current and voltage errors are appreciably reduced by the modification in the shape of the core laminations.

In Fig. 5 there is illustrated the principle of operation of the arrangement for diminishing current errors. The particular shape and construction of laminations shown are found to give satisfactory results using the nickel-iron composition of approximately 47% nickel. This alloy has a magnetization curve shaped approximately as shown by the curve E in Fig. 5 with the upper portion F departing materially from a straight line represented by the dotted continuation of the lower portion of the curve. In the case of the five-ampere instrument the point of departure from linearity occurs at approximately the eight-ampere point. The curve G represents the portion of the flux shunted by the projections B of the A-shaped laminations, and it will be observed that in these laminations saturation begins also approximately at the eight-ampere point, which is accomplished by the suitable selection of the number and shape of the laminations. Beyond the point of beginning saturation the shunted flux becomes a smaller and smaller percentage of the total flux and the resultant flux crossing the air gap represented by the curve H continues linearly for a greater distance than the curve E, for example, to a point J which is very nearly the twelve-ampere point.

The method of supporting the various parts of

the apparatus will be seen more readily from Fig. 2 showing an enclosing casing 29, partially broken away, in which the E-shaped frame 30 is secured for supporting the parts of the instrument. It will be seen that the frame 30 includes a pair of relatively long, narrow, upwardly extending arms 31 and 32 and, in the ends of these arms, suitable bearings or jewels 33 and 34 are mounted, which have hard surfaced cup-shaped 5 depressions in which mechanical pivot points 35 and 36 formed at the ends of the shaft 16 are permitted to rotate. A relatively wide and spreading arm or bracket 37 is provided at the intermediate portion of the frame 30 for supporting the field laminations 17 by means of suitable bolts 38. The core laminations 18 are likewise secured to the bracket 37 by means of suitable bolts 39.

A pointer 40, and if desired, a suitable damping 20 vane, not shown, are secured to the shaft 16 and it will be understood that suitable means such as lead-in spirals, not shown, for connecting the potential terminals of the instrument to the rotatable coil 11 and a biasing spring, not shown, 25 are also provided. The scale, not shown, for co-operation with the pointer 40, it will be understood, is to be mounted within the front cover 41 of the casing 29 and may be secured to the arm 31.

The construction lends itself to convenient and 30 expeditious assembly. The assembly may be carried out in the following manner. After the coil 11 has been mounted upon the shaft 16 the shaft 16 may be inserted between the bearings 33 and 34 and secured by a suitable longitudinal adjustment of the bearings. By turning the coil 11 to 35 a horizontal position, core 18 may be slipped through the coil 11 and over the shaft 16, whereupon the core 18 is bolted to the bracket 37 of the frame 30. After the field coil 13 has been slipped on to the pole piece 15 and secured there- 40 to, the field member 17 may be passed longitudinally of the shaft 16 past the arm 32 around the pole piece 14 and is also bolted to the bracket 31. It will be understood that other parts, not 45 shown, such as the scale plate, etc. may be secured to the front bracket 31 of the frame 30 and that additional supporting posts 42 may be provided for securing the scale plate, as well as the back plate 43 of the casing 29 to the field structure for increasing the rigidity of the 50 assembly.

If the apparatus is to be used as a voltmeter or an ammeter, it will be understood that the coils 11 and 13 may be connected in series, whereas if it is to be used as a wattmeter, the field coil 13 55 will be connected in series to the load directly or to a suitable transformer and the potential coil 11 will be connected between the lines of the circuit tested or between the output terminals of the potential transformer in series with a suitable 60 multiplier resistance. Assuming that the apparatus is used as a wattmeter it will be seen that the current flowing through the field coil 13 produces a magnetic flux crossing the air gap 12 and that the current flowing through the conductors on 65 the outer side of the coil 11 reacts with this flux to produce a torque causing the shaft 16 and the pointer 40 to deflect in opposition to the biasing spring, not shown. There is a tendency for the current flowing through the coil 11 to cause a flux 70 to pass through the stationary iron of the apparatus, up one leg 19 of the U-shaped core 18, down leg 20, through the branch 28, and down

branch 27 to the end of the core 18, or vice versa. This flux, however, serves no particular purpose as it is only the flux from the coil 11 crossing the air gap 12 and reacting with the torque produced by the coil 13 that produces torque. If the idle 5 flux produced by the coil 11, however, should be excessive it would tend to increase the inductance and decrease the power factor of the potential circuit and might also produce saturation effects which, in turn, may lead to wave form errors. 10 To obviate this tendency, the air gaps 23 and 24 are provided between the end portions 21 and 22 of the field member 17 and portions 19 and 20 of the core 18.

In accordance with the provisions of the patent 15 statutes, I have described the principle of operation of my invention together with the apparatus which I now consider to represent the best embodiment thereof but I desire to have it understood that the apparatus shown is only illustrative and that the invention may be carried out by other means.

What I claim as new and desire to secure by Letters Patent of the United States, is:

1. A long range dynamometer instrument comprising a field structure including a pair of pole pieces with an annular air gap therebetween and portions joining said pole pieces to form a magnetic circuit completed by passage of flux across said air gap, a field coil linking said field structure, at least one of said pole pieces being substantially annular in shape with a gap therein with branched circuit portions extending from the annular pole piece from either side of the gap therein to the flux conducting portion of the field structure, and a rotatable coil linking said annular pole piece with one side passing through it and an axis of rotation passing through said annular pole piece, one of said pole pieces being provided with flux shunting members at the ends of said air gap, said flux shunting members having a smaller cross-section than the main portion of the magnetic circuit and tending to saturate when the rated current of the field coil is exceeded. 45

2. A long range dynamometer instrument comprising a field structure built up of laminations including a pair of pole pieces with an annular air gap therebetween and portions joining said pole pieces to form a magnetic circuit completed by passage of flux across said air gap, a field coil linking said field structure, at least one of said pole pieces being substantially annular in shape, and a rotatable coil linking said annular pole piece with one side passing through it and an axis of rotation passing through said annular pole piece, the laminations of said field structure including laminations having projecting portions at the ends of said annular air gap shunting said air gap and tending to become saturated. 55

3. A dynamometer instrument comprising a field structure composed of magnetizable material including a pair of pole pieces with an annular air gap therebetween and portions joining said pole pieces to form a magnetic circuit completed by passage of flux across said air gap, a field coil linking said field structure, and a movable coil consisting of current conductors so mounted as to travel through said air gap as the coil moves, said field structure including a saturable portion shunting the air gap. 70
